[57] CLAIM

The ornamental design for a magnetic tape drive unit for a computer system, as shown and described.

DESCRIPTION

FIG. 1 is a perspective view showing the front and left side of a magnetic tape drive unit for a computer system showing my new design;

FIG. 2 is a front elevational view thereof;

FIG. 3 is a side elevational view showing the right side thereof;

FIG. 4 is a top plan view thereof;

FIG. 5 is a bottom plan view thereof;

FIG. 6 is a side elevational view showing the left side thereof;

FIG. 7 is a rear elevational view; and

FIG. 8 is a front perspective view similar to FIG. 1 but showing the door in the open position.

*FIG. 1**FIG. 2**FIG. 3**FIG. 4*

FIG. 5

FIG. 6

FIG. 7

FIG. 8
